FLARED-RATIO DIFFERENTIAL RELAY AND
AUXILIARY TRANSFORMER THEREFOR

William K. Sonnemann, Newark, N. J., assignor
to Westinghouse Electric & Manufacturing
Company, East Pittsburgh, Pa., a corporation
of Pennsylvania

Application December 28, 1939, Serial No. 311,377

15 Claims. (Cl. 175—294)

My invention relates to high-speed ratio-differential relays, that is, to high-speed relays which operate when the apparent difference between the currents entering and leaving a piece of apparatus exceeds a predetermined ratio or proportion of the apparent sum of said currents, thus operating on a ratio or proportion, independently of the size or magnitude of the difference-currents. More particularly, my present invention relates to means for obtaining a "flared" operating characteristic in such a relay, that is, a characteristic such that a larger ratio or percentage is required under certain circumstances, such as when the currents involved are abnormally large, or when the difference-currents are greatly out of phase with the additive currents, or when there is an asymmetrical current-wave due to the presence of a direct-current component.

The need for a flaring-ratio characteristic, when the currents are abnormally large, is apparent from the fact that the currents are measured by current-transformers which are usually of a certain order of commercial accuracy. When a large number of commercial transformers of nominally the same rating and characteristics are manufactured, there is inevitably a certain amount of difference in the individual characteristics of different transformers, particularly under heavy overload conditions when the transformers become saturated, and when their various degrees of saturation may vary considerably, from transformer to transformer. In actual commercial installations, it frequently happens, also, that current-transformers of different makes, or of different ratings, are utilized to respond to the currents in the incoming and outgoing leads of an apparatus to be differentially protected, and in these cases, the difference between the transformer-characteristics is, of course, very much magnified. It is usually desirable to be able to detect even weak fault-currents when there is an internal fault in the differentially protected apparatus, which may be the winding of a generator or a power-transformer. It is also invariably desired that there shall not be a response of the differential relay to the apparent difference-currents which result from differences in the individual calibration or performance of the respective current-transformers when the same current is flowing into and out of the protected apparatus, such as the previously mentioned winding of a generator or a power-transformer.

To prevent faulty operations of the ratio-dif-

ferential relay as a result of these, sometimes large, differences between the secondary currents of two current-transformers, the primaries of which are traversed by the same current entering and leaving the protected apparatus, a flared-ratio characteristic has been previously sought, and obtained, either by reducing the effectiveness of the relay-operating currents, or difference-currents, or by increasing the effectiveness of the relay-restraining currents, or summation-currents, during high-current conditions as compared to low-current conditions. I have found, however, that it is not enough, simply to cause the ratio-characteristic to become flared under heavy-current conditions, when the difference-current is substantially in phase with the summation-currents, and when the current-waves are substantially symmetrical.

Thus, I have ascertained that many faulty operations of differential relays have been obtained, in the past, under conditions in which the apparent difference-currents, or the differences between the secondary currents of two current-transformers whose primaries are identically excited, are frequently considerably out of phase with the "through"-currents flowing through the primaries, due to an external fault; and this difference is largely unpredictable, depending upon which one of the current-transformers is saturated first, or has a more rapidly drooping characteristic than the other one. I have found this difficulty, due to out-of-phase conditions, even with differential-relays which had a decidedly flared characteristic for in-phase currents. In designing a generally acceptable flared-ratio differential relay, I have found it to be necessary, therefore, to cause the relay to have just as much of a flared characteristic for out-of-phase operating and restraining currents, as for in-phase currents, and it is even desirable to have a greater flaring, for out-of-phase conditions, because true fault-currents are likely to be more in phase with the restraining currents which are impressed upon the differential relays as a result of any through-load which is carried by the faulted protected apparatus, such as a winding of a generator or a power-transformer, at the time of the fault.

I have also discovered that asymmetrical fault-currents have frequently been the cause of faulty operation of previous ratio-differential relays, either of the straight-ratio type, or of the so-called flared-ratio type. The reason for this, is that an asymmetrical fault-current contains a direct-current component, which is like a half-

wave of non-sinusoidal pulsating current of a half-wave length extending over a large number of cycles of the line-frequency current, usually 60 cycles. In an asymmetrical current-wave, the line-frequency, or 60-cycle, wave-form of the current is superimposed over this direct-current component, making the resultant pulsations of the wave-form asymmetrical with respect to the zero-current axis, hence the term asymmetrical. When such direct-current components appear in the primary currents which are passed through the two current-transformers at the entrance and exit terminals of the protected apparatus, the direct-current component almost invariably saturates the current-transformers, and usually saturates them initially at different times and each for a different length of time.

My investigations have led me to believe that the resultant effect of asymmetrical-current saturation, upon the difference-currents derived from the two current-transformers, is that it results in a very large difference-current with a considerable direct-current component, and of relatively brief duration, as compared with the duration of the direct-current component in the asymmetrical primary-current waves. As these difference-currents are utilized as the operating currents of the relay, I believe that this unidirectional-current component of the asymmetrical wave-form of the difference-currents has frequently been a source of erroneous operation of ratio-differential relays, where asymmetrical fault-currents have been encountered. The seriousness of this difficulty will be realized when it is remembered that whenever a short-circuit happens to occur at a point which is relatively close to a large generating source, or where the time-constant is long, and at the moment when the impressed voltage-wave is at zero, or anywhere close to a minimum or zero-value, the resultant fault-current wave will be considerably distorted or asymmetrical with respect to the zero-current axis. In other words, relays must be designed to operate properly, with asymmetrical fault-currents.

With the foregoing considerations in view, the principal object of my invention is to provide a novel type and arrangement of auxiliary transformer which is utilized in combination with a ratio-differential relay, to give the relay a ratio-characteristic which is flared or increased, either when the operating current is large, or when it is greatly out of phase with the restraining current, or when it has a direct-current component.

More specifically, it is an object of my invention to provide an auxiliary transformer built on a three-legged core having a central leg on which the primary and secondary restraint-current windings are disposed, and having two outer legs on which the operating-current primary and secondary windings are disposed, the design being such that the operating-winding currents produce a flux circulating in the two outer legs and saturating said legs during certain portions of the cycle, thereby in effect removing the return-flux portions of the magnetic circuit from the center leg which carries the restraint-windings, and thus producing the desirable characteristics which I have mentioned.

With the foregoing objects in view, and other more detailed objects which will be apparent as the description proceeds, my invention consists in the parts, elements, combinations, systems and methods hereinafter described and claimed, and

illustrated in the accompanying drawings, wherein:

Figure 1 is a diagrammatic view of circuits and apparatus illustrating my invention in a preferred form of embodiment, and illustrating its mode of application to a protected apparatus;

Fig. 2 is an enlarged fragment of some of the current-wave forms which are obtained in my apparatus;

Figs. 3 and 4 are curve-diagrams illustrating the relation between the value of the operating current which is necessary to cause a relay-operation for various phase-angles of the operating current with respect to the restraining current, and for various values of the restraining current;

Fig. 5 is a curve-diagram illustrating the flared-ratio characteristic of my relay, as compared to a constant-ratio relay, both with in-phase currents and with out-of-phase currents;

Fig. 6 is a copy of some of the traces obtained with a multiple-element oscillograph, showing the performance of my relay in the presence of asymmetrical fault-currents; and

Figs. 7 and 8 are copies of some of the traces obtained with a multiple-element oscillograph, illustrating the performance of my improved relay during in-phase conditions and out-of-phase conditions, respectively.

In Fig. 1, I illustrate my invention as being utilized to protect (or to detect internal faults in) a single-phase generator G having a current-input terminal 9 and a current-output terminal 10, the input and output currents being derived for relaying purposes, by current-transformers 11 and 12, respectively, having secondary currents which are indicated as I_3 and I_1 , respectively. For convenience of reference, in the following description, I shall visualize the secondary current I_1 as being the larger current, so that there will be a difference-current $I_2 = I_1 - I_3$. Of course, it will be understood that either I_1 or I_3 may be the larger, and that the foregoing convention or designation is adopted merely for convenience. It will also be understood that either one of the terminals 9 or 10 may be the input terminal, the particular designation being again merely for convenience.

My invention is particularly related to high-speed ratio-differential relays, and I have illustrated the invention, in Fig. 1, in combination with a balanced-beam type of instantaneous ratio-differential relay which comprises, typically or in general, a balanced beam 13, of magnetizable material, which is weighted at 14 at its back end, and which has electrical contacts 15 at its front end, for controlling a relay-circuit 16 which may be utilized for any desired purpose, either for indication or for automatic operation or control or correction of an internal fault-condition in the protected generator G. The beam 13 is intermediately pivoted on a pivot 17. Its front end is attracted by an operating winding O which is wound on a magnetic structure 18, while its rear end is attracted by two restraint-windings R_1 and R_2 which are mounted upon a multiple-legged magnetic structure 19. Two restraint-windings are utilized, by preference, so that one of said windings, R_1 as illustrated, can be connected in series with a resistor 21, while the other one, R_2 is connected in series with a capacitor 22, so as to produce two out-of-phase pulsating restraining forces on the beam 13, so that the restraining force never passes through zero.

In the normal use of a differential relay such as that which is shown in Fig. 1, the operating winding O is normally energized in accordance with $I_2 = (I_1 - I_3)$, while the restraint-winding or windings R_1 and R_2 are energized in accordance with $(I_1 + I_3)$. When the ratio-differential relay is directly energized in accordance with these so-called additive and differential currents, respectively, the relay has a substantially straight-line characteristic, such as is represented by the line 24 in Fig. 5, when the restraint-current is in phase with the operating-current. I have discovered, however, that such a relay has inherently a much lower ratio-characteristic when the restraint-current is considerably out of phase with the operating-current, because in such a case, the maximum force developed by the operating winding O occurs at a time when the force developed by the restraint-winding or windings R_1 and R_2 is at a minimum. This reduced-ratio out-of-phase characteristic of a straight-line or constant-ratio relay is indicated by the line 25 in Fig. 5.

In accordance with my invention, I provide means for causing the ratio-differential relay to depart from the constant-ratio characteristic just described. In the preferred form of embodiment which is illustrated in Fig. 1, I utilize, for this purpose, an auxiliary transformer having a three-legged iron core 27 having a central leg 28 and two outer legs 29 and 30. I pass the summation-current $(I_1 + I_3)$ through a primary winding 32 which is disposed on the central leg 28, accomplishing this purpose by connecting the outer terminal of the first current-transformer 12 to the terminal 1 of the auxiliary transformer, which terminal is connected to one end of the primary winding 32, and connecting the outer terminal of the second current-transformer 11 to the terminal 3 of the auxiliary transformer, the latter terminal being connected to the end of the primary winding 32, while the inner terminals of other end two current-transformers 11 and 12 are connected together as indicated at 33. This primary winding 32 is utilized for the purpose of energizing the restraint windings R_1 and R_2 of the ratio-differential relay, a high-voltage secondary winding 34 being disposed on the aforesaid central leg 28, for this purpose, as illustrated in Fig. 1.

I utilize two identical primary windings 35 and 36 for developing the flux which produces the secondary current I_0 energizing the operating winding O of the ratio-differential relay, these two operating-current primary windings 35 and 36 being respectively disposed on the two outer legs 29 and 30 of the auxiliary transformer. The two operating-current primary windings 35 and 36 are connected in series with each other, between the central point 37 of the restraint-current primary winding 32 and the aforesaid common return-point 33 of the two current-transformers 11 and 12, so that the two operating-current primary windings 35 and 36 are traversed by the difference between the current-transformer currents I_1 and I_3 , said difference-current being designated I_2 . Each of the outer legs 29 and 30, where the operating-coil primary windings 35 and 36 are disposed, is provided with an operating-current secondary winding, these two secondary windings being designated by the numerals 39 and 40, respectively. These two operating-current secondary windings 39 and 40 are connected in series with each other, and are

utilized to energize the operating coil O of the ratio-differential relay.

The two operating-current primary windings 35 and 36 produce fluxes which both circulate around the two outer legs 29 and 30 in the same direction, so that, because of the balanced construction, there is substantially no magnetomotive force tending to divert any of said fluxes through the center leg 28, assuming that the relative conditions of saturation of the two outer legs 29 and 30 remain substantially identical. Consequently, the operating-current flux ϕ_0 is opposed by the restraint-current flux ϕ_R , in one of the outer legs, such as the leg 30, as indicated by the arrow $(\phi_0 - \frac{1}{2}\phi_R)$, while, in the other leg, such as the leg 29, the operating-current flux is augmented by the restraint-current flux, as indicated by the arrow $(\phi_0 + \frac{1}{2}\phi_R)$, representing conditions prevailing at some assumed instant within the auxiliary transformer.

The manner of operation of the apparatus which has just been described, with reference to Fig. 1, will perhaps best be understood with reference to some tests which I have made on a particular form of embodiment of the auxiliary transformer, the iron core of which is indicated, full scale, at 27 in Fig. 1. While I am not limited to any particular size or proportions of either the magnetic or electrical circuits of this transformer, it may be helpful, to fix our ideas on some one particular design, to mention the fact that the particular tested transformer to which I shall refer had a restraining-current primary winding 32 having four turns, two operating-current primary windings 35 and 36 having 120 turns each, a restraint-current secondary winding 34 having 1200 turns, and two operating-current secondary windings 39 and 40 having 15 turns each.

Fig. 7 shows the results of oscillographic tests which were made upon such a transformer, in order to study its performance. A substantially sinusoidal 60-ampere, 60-cycle, current I_3 was caused to flow through the terminal 3, with other connections such as to apply a substantially sinusoidal 60-cycle voltage tending to produce a differential current-flow I_2 . The first two traces, in Fig. 7, show these currents I_3 and I_2 respectively. The third and fourth traces respectively show the relay-restraining voltage E_R which was developed in the secondary winding 34, and the relay-operating current I_0 delivered by the two serially connected secondary windings 39 and 40. The last two traces, in Fig. 7, show the wave-form of the currents flowing in the respective restraint-windings R_1 and R_2 , the former having the resistor 21 connected in series with it, while the latter had the capacitor 22 connected in series with it.

For a first analysis, reference will be made to Fig. 2, in which I have reproduced the wave-forms of I_3 , I_2 and I_0 , as derived from the first, second and fourth traces of Fig. 7. I explain the operation of the auxiliary transformer as follows. During the short period from a to b , the auxiliary transformer is unsaturated, thus tending to limit the differential-current I_2 to a small value which would have reached a peak value as indicated by dotted lines at e in Fig. 2. During this time, from a to b , the auxiliary transformer was performing with its true ratio, so that its secondary current I_0 was increasing normally from a to b , and would have reached a peak value as indicated by dotted lines at f , if the transformer-ratio had not broken down tremendously.

However, at the point *b* the iron became saturated, producing a sudden rise of the differential-current I_2 , to the value *g*. I visualize this sudden rise in the differential current I_2 as being caused by the fact that the operating-current primary-coils 35 and 36 of the transformer were unable to resist the voltage impressed thereon, so that a high peak value of current resulted, as indicated at *g*. At the same time, since the outer legs 29 and 30 of the core were badly saturated, the operating-current secondary windings 39 and 40 could not function in a normal manner, so that the secondary current I_0 began to decay rapidly from the point *b* to the point *c*.

Now referring back to Fig. 7, it will be noted that, during the time from *a* to *b*, when the two outer legs 29 and 30 of the auxiliary transformer were unsaturated, the center-leg primary and secondary windings 32 and 34 (Fig. 1) will behave relatively normally, that is, the secondary voltage E_R was increasing rapidly, at the same time when the primary current I_3 was increasing. Between the times indicated by the lines *b* and *c*, however, the two outer legs 29 and 30, which constitute the return-path for the magnetic flux ϕ_R of the center leg 23, became so thoroughly saturated that the transformer-windings 32-34 on the center leg have, in effect, an air (or non-magnetic) return-circuit for the center-leg flux ϕ_R , even though the central core 23 may be unsaturated. During this saturated period from *b* to *c*, therefore, the transformation-ratio of the center-leg transformer 32-34 breaks down, so that the secondary voltage E_R falls off rapidly, as indicated in Fig. 7.

The result of the foregoing considerations is that, on the outer legs 29 and 30, there is, in effect, a saturating operating-current transformer which reduces the magnitude of the operating current I_0 when excessive difference-current conditions I_2 exist, thus tending to produce the desired flared characteristic. Furthermore, on the center leg of the same iron assembly 27, there is provided another transformer 32-34, for exciting the restraint-windings R_1 and R_2 , and this restraint-current transformer 32-34 has its operation also modified in accordance with the condition of saturation of the outer legs 29 and 30 resulting from the magnitude of the difference-current I_2 .

The exact nature of the effect of the difference-current saturation, in the outer legs 29 and 30, upon the operating characteristics of the restraint-current transformer 32-34 on the central leg 23, will best be understood by reference to Fig. 8 in comparison with Fig. 7.

The films which are reproduced in Figs. 7 and 8 differ in that the Fig. 7 film was taken for conditions in which the differential-current I_2 was approximately in phase with the through-current I_3 , whereas the Fig. 8 film was taken for the case in which the difference-current I_2 was leading the through-current I_3 by approximately 90°. A comparison of the two films will show that there is very little difference in the operating-coil currents I_0 which were obtained, in the two cases, the first one having a peak-to-peak value of 11.8 amperes, and the second one having a peak-to-peak value of 10.4 amperes. This shows that the outer legs 29 and 30 of the auxiliary transformer were operating approximately the same, regardless of the phase of the magnetizing currents on these legs, as compared with the phase of the magnetizing current for the central leg 23. When a comparison is made of the relay-

restraining voltages E_R , however, a considerable difference will be discovered between Figs. 7 and 8. When the currents were in phase, as in Fig. 7, the peak-to-peak value of the restraint-voltage E_R was 200 volts, whereas, when the currents I_2 and I_3 were 90° out of phase, the peak-to-peak value of the restraint-voltage E_R was 575 volts, indicating a much stronger restraint in the case of the out-of-phase currents.

- 10 I explain this increased restraint, when the primary currents I_2 and I_3 are 90° out of phase, by noting that, when the currents are in-phase, as shown in Fig. 7, the unsaturated period *a*-*b* (as determined by the relatively flat part of the I_2 wave) occurs at a time when the transformer-flux due to the I_3 current is close to the zero point, whereas, when the currents are 90° out of phase, the outer legs of the transformer are unsaturated when the I_3 current, and hence its flux, are very close to their maximum values, on the central leg 23 of the auxiliary transformer, so that the central-leg transformer 32-34 has its normal high transformation-ratio, inducing a high voltage E_R in the secondary winding 34.
- 15 20 Reference to the last two traces in each of Figs. 7 and 8 will show a considerable increase in the areas of the restraint-winding currents I_{R1} and I_{R2} in the Fig. 8 film representing the out-of-phase conditions. The difference in the relay-conditions shown in Figs. 7 and 8 is witnessed also by the fact that the relay operated, under the conditions depicted in Fig. 7, whereas the relay did not operate, under the conditions depicted in Fig. 8.
- 25 30 35 It will be noted, in connection with the explanation of the saturating operation of the auxiliary transformer, that I utilize an outer-leg flux ϕ_0 , which is at least several times larger than the central-leg flux ϕ_R , so that, during saturated operating conditions, when the flux in one of the outer legs is $(\phi_0 - 1/2\phi_R)$ and the flux in the other outer leg is $(\phi_0 + 1/2\phi_R)$, these two fluxes will both be nearly enough of the same value, because both are well out on the flat part of the magnetization-curve of the transformer, representing highly saturated conditions.

- 40 Thus, referring to Fig. 5, it will be seen that, for a through-terminal current I_3 of 60 amperes, the minimum in-phase difference-current I_2 necessary to cause a relay-operation is 12 amperes, which means that the I_1 through-terminal current will be $60 + 12 = 72$ amperes. The operating-current transformer on the two outer legs 29 and 30 (Fig. 1), under these conditions, has a magnetomotive force corresponding to $12 \times 240 = 2880$ ampere-turns in the two 120-turn primary windings 35 and 36, whereas the restraint-current transformer on the central leg 23 has a magnetomotive force corresponding to $(60 + 72) \times 2 = 264$ ampere-turns in the primary winding 32.

- 45 50 55 60 In the particular form of embodiment of my invention which is shown in Fig. 1, the restraining windings R_1 and R_2 of the differential relay impose an extremely low volt-ampere burden on the E_R secondary winding 34 on the central leg 23 of the auxiliary transformer, and it was found that this current-transformer burden was too low to prevent excessive saturation of the central leg 23, with the normal size of phase-shifting resistance 21 and capacitance 22 which were normally utilized in other applications, as, for example, in impedance-relays. Rather than increase the burden of the restraint-coils R_1 and R_2 , which would necessitate utilizing a larger leg 23 (and hence more expensive) capacitor 22, and

additional development to determine the proper values of the new magnitudes, I have corrected this low-burden difficulty by adding an artificial burden in the form of a resistor 50, as shown in Fig. 1. Instead of using this shunt-connected artificial load or burden 50, I could have redesigned the auxiliary transformer to utilize either a smaller number of primary turns 32 on the central leg 28, or I could have short-circuited a small percentage of the turns in the winding 34, so that the central leg 28 would not saturate before, say, 10 to 15 amperes, (or two or three times normal load-current), were passed through the primary winding 32, even with the low-burden restraint-windings R_1 and R_2 of the particular form of differential relay which I utilized.

The performance of my relay, with respect to various-phase-angles between the operating-current I_2 and the restraint-current I_3 , is well shown in the test-curves reproduced in Figs. 3 and 4, which show the minimum operating-currents I_2 necessary to cause a relay-operation, under different conditions of restraint. It will be noted that a fairly flat curve is obtained for a restraint of $I_3=5$ amperes, corresponding to normal-load conditions of the current-transformers 11 and 12, and hence corresponding to normal full-load conditions of the protected apparatus G in Fig. 1. Thus, in Fig. 3, it will be seen that the minimum operating-current I_2 , necessary to trip the relay with normal-load restraint, varies only between the limits of .24 ampere and .36 ampere, no matter what the phase-angle between I_2 and I_3 . On the other hand, as the restraint-current I_3 increases, it will be seen, from Figs. 3 and 4, that the curves for the minimum values of the operating-current I_2 slope sharply upwardly when the phase-angle departs greatly from the in-phase condition, producing the desired concave, or upwardly flared, curve representing the relation between the operating-current I_2 and phase-angle. It will be noted that this is just the reverse of previous ratio-differential relay performances, in which this curve had a convex form, of a type requiring something like three or four times as much operating-current I_2 to operate the relay, when the currents I_2 and I_3 are in-phase, as when said currents are 90° out of phase.

The operational characteristics of my flared-ratio relay are summarized in the curves 51, 52 and 53 of Fig. 5, utilizing values which are taken from the test-values which are reproduced in Figs. 3 and 4. The difference in operation of my relay, as compared with an old constant-ratio relay, will be readily apparent, by comparison with the straight-line curves 24 and 25 of the same figure.

An important feature of my improved relay is also that it is much better able to resist faulty operations in response to asymmetrical fault-currents, than previous relays. The tests which were recorded by the films reproduced in Figs. 7 and 8 were taken for artificial test-conditions utilizing substantially symmetrical currents such as I_3 . In actual applications of the relay, it is necessary for the relay to operate properly when the impressed currents have a strong asymmetrical, or direct-current, component.

In order to verify the operation under such conditions, a test, as recorded by the film which is reproduced in Fig. 6, was made, in which the primary current was made to have a direct-current component, 54, as shown in the third trace in Fig. 6. It will be noted that, under these

conditions, the difference-current I_2 developed a strong asymmetrical, or direct-current, component, 55, which was relatively highly damped with respect to the primary-current asymmetrical component 54, as evidenced by the fact that the difference-current asymmetrical component 55 reduced substantially to zero value much more quickly.

The transformer-operation, as depicted in Fig. 6, may be interpreted as follows. The direct-current component 55 of the difference-current I_2 saturates the two outer legs 29 and 30 (Fig. 1) of the auxiliary transformer with a unidirectional bias, and when this occurs, the operating current I_0 which is produced in the secondary windings 39 and 40 on the same legs is not very high, notwithstanding the fact that the primary currents I_2 on the same leg have extremely high peaks. Toward the end of the film, it will be noted that the primary current I_2 diminishes to a very small value, and yet there is a very material value indicated for the secondary current I_0 on the same legs of the transformer. This can be explained by the absence of the direct-current saturation during the latter portions of the film, which restores the normal transformation-ratio to the outer-leg transformer. It will be further noted that the central-leg secondary voltage E_R is distorted, and somewhat limited, because of the direct-current component 55 in the I_2 current during the early portions of the film, indicating that the return-path of the central-leg flux, through the two outer legs 29 and 30, is saturated at this time. As a matter of fact, the differential relay did not respond, during the test-conditions depicted in Fig. 6, notwithstanding the presence of very high operating-current peaks due to the presence of the direct-current component 55 in the I_2 -trace.

It will thus be seen that my auxiliary transformer, which is built on the three-legged core 27, provides a very simple means for giving a ratio-differential relay a flared ratio-characteristic which will enable it, not only to automatically increase the ratio between difference-current and through-current at which the relay will operate during excessive-current conditions when current-transformer saturation is inevitably obtained, but which will also enable it to have a still more steeply flared ratio-characteristic when the difference-current is greatly out-of-phase with respect to the through-current, which is normally the case when there is an external fault resulting in heavy through-currents, and which will also enable the relay to have a flared characteristic during asymmetrical current-conditions, so as to enable the relay to ride through severe asymmetrical current-conditions without a faulty relay-operation.

While I have illustrated my invention in accordance with a preferred form of embodiment, and while I have described the same in accordance with my best present understanding of its theory of operation, I do not wish to be limited, in either respect, to all of the details shown and described, as it should be obvious that various changes may be made, by those skilled in the art, without departing from the essential principles of my invention, particularly in its broader aspects. I desire, therefore, that the appended claims shall be accorded the broadest construction consistent with their language and the prior art.

I claim as my invention:

1. A flared-ratio differential-relay assembly

for use in connection with current-responsive input and output transforming-means for deriving additive and differential relaying-currents, respectively, from a differentially protected device, said differential-relay assembly comprising the combination, with said relaying-current transforming-means, of a differential relay element having an operating winding or windings and a restraining winding or windings, and an auxiliary transformer, said auxiliary transformer having a three-legged magnetizable core having a center-leg magnetic circuit and an outer-leg magnetic circuit, an additive-current primary winding-means and a restraining-current secondary winding-means both disposed upon one of the magnetic circuits of the auxiliary transformer, a differential-current primary winding-means and an operating-current secondary winding-means both disposed upon the other magnetic circuit of the auxiliary transformer; the additive-current primary winding-means being electrically connected so as to circulate an additive-current flux around its magnetic circuit of the auxiliary transformer, the differential-current primary winding-means being electrically connected so as to circulate a differential-current flux around its magnetic circuit of the auxiliary transformer, the operating-current secondary winding-means being electrically connected so as to energize the operating winding or windings of the differential relay element, and the restraining-current secondary winding-means being electrically connected so as to energize the restraining winding or windings of the differential relay element.

2. The invention as defined in claim 1, characterized by relative proportions of the numbers of turns and loads such that the magnetic flux in one of said magnetic circuits is at least several times larger than the magnetic flux in the other of said magnetic circuits during the operative conditions of the device.

3. The invention as defined in claim 1, characterized by the fluxes and core-cross-sections of the auxiliary transformer being so related that one of said magnetic circuits saturates sooner than the other, during excessive-current operating-conditions of the device.

4. The invention as defined in claim 1, characterized by the fluxes and core-cross-sections of the auxiliary transformer being so related that at least one of said magnetic circuits becomes badly saturated during excessive-current operating-conditions of the device.

5. The invention as defined in claim 1, characterized by relative proportions of the numbers of turns and loads such that the differential-current magnetic flux is at least several times larger than the additive-current magnetic flux during the operative conditions of the device.

6. The invention as defined in claim 1, characterized by the fluxes and core-cross-sections of the auxiliary transformer being so related that the outer legs saturate sooner than the central leg during excessive-current operating-conditions of the device.

7. The invention as defined in claim 1, characterized by the fluxes and core-cross-sections of the auxiliary transformer being so related that the outer legs badly saturate during excessive-current operating-conditions of the device.

8. A flared-ratio differential-relay assembly for use in connection with current-responsive input and output transforming-means for deriving additive and differential relaying-currents, re-

spectively, from a differentially protected device, said differential-relay assembly comprising the combination, with said relaying-current transforming-means, of a differential relay element 5 having an operating winding or windings and a restraining winding or windings, and an auxiliary transformer, said auxiliary transformer having a three-legged magnetizable core, an additive-current primary winding-means and a restraining-current secondary winding-means both disposed upon the central leg of the auxiliary transformer, a differential-current primary winding-means and an operating-current secondary winding-means both disposed upon one of the outer legs of the auxiliary transformer, and a similar pair of differential-current primary winding-means and operating-current secondary winding-means both disposed on the other outer leg of the auxiliary transformer; the two differential-current primary winding-means being electrically connected so as to cumulatively circulate a differential-current flux around the two outer legs of the auxiliary transformer, the two operating-current secondary winding-means 20 being electrically connected so as to energize the operating winding or windings of the differential relay element, and the restraining-current secondary winding-means being electrically connected so as to energize the restraining winding or windings of the differential relay element.

9. The invention as defined in claim 8, characterized by relative proportions of the numbers of turns and loads such that the differential-current magnetic flux circulating around the two outer legs is at least several times larger than the additive-current magnetic flux in the central leg during the operative conditions of the device.

10. The invention as defined in claim 8, characterized by the fluxes and core-cross-sections of 40 the auxiliary transformer being so related that the outer legs saturate sooner than the central leg during excessive-current operating-conditions of the device.

11. The invention as defined in claim 8, characterized by the fluxes and core-cross-sections of the auxiliary transformer being so related that the outer legs badly saturate during excessive-current operating-conditions of the device.

12. Electrical translating-apparatus comprising, in combination, two diverse input-circuits, two diverse output-circuits, and a transformer for coupling said output-circuits to the respective input-circuits, said transformer having a three-legged magnetizable core, primary and secondary winding-means disposed on the central leg of the core, primary and secondary winding-means disposed on, and divided between, the two outer legs of the core so as to cumulatively circulate their magnetic flux around said outer legs, circuit-connections for energizing the respective central-leg and outer-leg primary winding-means from the respective input-circuits, and circuit-connections for energizing the respective output-circuits from the respective central-leg and outer-leg secondary winding-means.

13. Cumulative and differential electrically-responsive translating-apparatus comprising, in combination, two differently energized source-current circuits for said apparatus, circuit-connections for deriving a cumulative input-circuit and a differential input-circuit responsive, respectively, to the sum and difference of electrical quantities in said source-current circuits, and saturable transforming-means for deriving cumulative and differential output-circuits in such

manner as to be responsive to the respective cumulative and differential input-circuits and also to be responsive in some measure to each other, said transforming-means comprising a transformer having an at least partially saturable three-legged magnetizable core, primary and secondary winding-means disposed on the central leg of the core, primary and secondary winding-means disposed on, and divided between, the two outer legs of the core so as to cumulatively circulate their magnetic flux around said outer legs, circuit-connections for energizing the respective central-leg and outer-leg primary winding-means from the respective input-circuits, and circuit-connections for energizing the respective output- 15

circuits from the respective central-leg and outer-leg secondary winding-means.

14. The invention as defined in claim 12, in combination with electrically responsive means 5 having an operating winding-means energized from one of said output-circuits and a restraining winding-means energized from the other output-circuit.

15. The invention as defined in claim 13, in 10 combination with electrically responsive means having an operating winding-means energized from said differential output-circuit and a restraining winding-means energized from said cumulative output-circuit.

WILLIAM K. SONNEMANN.
